MILK STOOL

Mike Black, Cincinnati, Ohio, assignor to H. H.
Nieberding, Cincinnati, Ohio

Application July 8, 1944, Serial No. 544,063

2 Claims. (Cl. 155—95)

1

This invention relates specifically to milk stools, particularly adapted for use in dairies by persons engaged in milking cows therein; although it will be made evident that the stool constitutes a facility applicable to use as a seat in various places, and that the scope of the invention is not limited by the use to which it is applied.

Objects of the invention are to provide a stool comprising a polypodous supporting frame having an annular bearing portion at its upper end, in combination with a seat having a retaining bracket attached to its underside and rotatively mounted on said bearing, and an attaching bearing device cooperating with said frame and said seat for rotatively holding the seat in a relationship in which said bracket operates on said bearing, leaving said seat free for rotation about a vertical axis while said frame remains stationary; to provide a portable and light-weight stool having a stationary supporting frame and rotary seat composed principally of light-gage or thin-gage sheet metal, thereby contributing substantially and effectively to the lightness of weight of the stool; and to provide a stool composed of a polypodous frame having an annular bearing rigidly connecting the upper ends of the legs thereof and provided with a central hole, in combination with a light-weight and thin-gage sheet metal seat having a bracket attached to its underside and rotatively supported by said bearing, and a central pivot device engaged in said hole and preventing both lateral and vertical displacement of the seat relative to the frame while leaving the seat freely rotative about the axis of said pivot device.

Another object of the invention is to provide a stool for general use as a seat and consisting of a light-weight metallic polypodous supporting frame made of thin-gage sheet metal parts, in combination with a seat composed principally of thin-gage and light-weight sheet metal, and means for pivotally holding said seat on said frame while leaving said seat free for rotation about a vertical axis and preventing displacement thereof in any direction.

Various other objects and advantages will be evident from the following description, reference being made to the annexed drawing, in which—

Fig. 1 is a side elevation of my improved polypodous stool.

Fig. 2 is an enlarged vertical sectional view showing the devices by which the seat is pivotally and rotatively retained upon and in connection with the supporting frame and held from displacement in any direction.

2

Fig. 3 is a sectional view on the line 3—3 of Fig. 2, looking in the direction of the arrows and showing a bottom plan view of the device by which the seat is rotatively held in connection with the supporting frame and prevented from displacement.

Fig. 4 is a top plan view showing attached crossed portions of the legs of the stool, looking from the plane 4—4 of Fig. 2.

In the embodiment of my invention shown, the polypodous supporting frame or pedestal comprises two pairs of sheet metal supporting legs which converge upwardly from attached crossed portions near their lower ends. The upper ends of the converging legs are rigidly secured to an annular bearing device for supporting the seat. It is evident that the number of legs may be varied as desired, and that the invention is not limited to an embodiment in which the legs are arranged in pairs.

A relatively narrow strip of sheet metal of relatively thin gage and light weight is shaped to form a standard of approximately A configuration and provide two upwardly converging legs 1 and 2 integrally connected at their lower ends by an inwardly bowed cross-bar having upwardly converging portions 3 and 4 and a substantially horizontal portion 5. The bearing portions 6 by which the legs 1 and 2 are integrally connected with the portions 3 and 4, respectively, are curved and rounded as shown, in order to present smoothly curved and rounded outer bearing surfaces that will not damage, deface or mar the floors, carpets or rugs upon which the stool may sometimes be used. The horizontal connection 5 is formed with a vertically displaced portion 7 for receiving and for attachment to a complementary part of the cooperating pair of legs.

The said cooperating pair of legs comprises a relatively narrow strip of sheet metal of relatively thin gage and light weight shaped to form and provide two upwardly converging legs 8 and 9 integrally connected at their lower ends by upwardly converging portions 10 and 11 and a substantially horizontal portion 12. The bearing portions 13 by which the legs 8 and 9 are integrally connected with the portions 10 and 11, respectively, are curved and rounded like the bearing portions 6 in order to present smoothly curved and rounded outer bearing surfaces that will not damage, deface or mar the floors, carpets or rugs upon which the stool may sometimes be used. The horizontal portion 12 crosses the horizontal portion 5 and seats in and against the vertically displaced portion 7 thereof. The crossed

parts 7 and 12 are rigidly attached together as by a rivet 14.

Each of the legs 1, 2, 8 and 9 has an attaching portion 15 on its upper end. The attaching portions 15 of all of the legs are engaged against an annular flange 16 of a circular sheet metal cap and rigidly attached thereto by welds 17 or otherwise, as desired. The flange 16 forms an integral part of an annular bearing 18. The annular bearing 18 is immediately above the flange 16 and is integrally connected by a wall having a domed or upwardly convexed central bearing portion 19 provided with a hole that is coaxial with the annular flange 16. The upper surfaces of the bearing 18 and the bearing portion 19 are preferably in the same horizontal plane.

The detachable and rotary seat of my improved stool comprises an approximately circular section of thin-gage and light-weight sheet metal shaped to form a horizontal seating portion 20, and an integral downwardly extended circumferential flange 21. The diameter of said seating portion 20 is considerably greater than the diameter of the annular flange 16. The diameter of said seating portion 20 also is substantially less than the distance between the lower ends of any pair of legs of the supporting frame. This prevents the stool from tilting, regardless of the distribution of weight on the seat. The downwardly extended flange 21 substantially strengthens the marginal portion of the seating portion 20, prevents bending and deformation thereof, and makes it possible to use light-weight sheet metal of smaller or thinner gage in forming the seating portion than would otherwise be possible.

The central part of the seating portion 20 of the thin-gage and light-weight metallic seat is strengthened and is prevented from bending or becoming deformed by a bearing device or hub extending centrally from the underside of the seat, cooperating with the bearing 18 and with the domed or upwardly convexed central portion 19 of the supporting frame. The said bearing device or hub consists of a central portion 22 preferably seating upon the domed or upwardly convexed central bearing portion 19 of the frame, and an annular portion 23 in integral connection with the margin of the central portion 22 and having a marginal flange 24 seating against and attached to the underside of the part 20 of the seat by welding 25 or otherwise. The annular portion 23 is in vertical continuation of the flange 16 so that the margin of the central portion 22 seats upon the bearing 18. This positively prevents the seat from becoming tilted or inclined upon the supporting frame, and yet leaves the seat freely rotative about the vertical axis of the central pivot device.

The said central pivot device is for holding the seat upon the frame, and for preventing both lateral and vertical displacement of the seat relative to the frame while leaving the seat freely rotative about the vertical axis of said pivot device. In the construction shown, a metallic body 26 is welded or otherwise rigidly attached to the upper side of the central portion 22. The said metallic body 26 is formed with a central screwthreaded hole 27 coaxial with the seat 20, and the central portion 22 is provided with a hole in continuation of the hole 27 and in axial alignment with the hole through the domed or upwardly convexed central bearing portion 19 of the frame. A member comprising an abutting end portion 28 extending through the hole in the domed or upwardly convexed central bear-

ing portion 19 of the frame into clamping engagement with the underside of the central portion 22 of the seat device, and a portion 29 of greater diameter than the hole in the domed or convexed portion 20 of the frame through which the portion 28 extends, constitutes a part of the means for pivotally holding the seat on the frame while leaving said seat free for rotation about a vertical axis, and for preventing displacement of the seat in any direction. The said member 28-29 has a hole which is brought in vertical axial continuation of the hole 27 when said seat 20 is shifted. An attaching screw 30 extends vertically through the hole in the member 28-29, through the hole in the central portion 22, and is detachably screwed into the threaded hole 27 in the metallic body 26 in a manner to clamp the member 28-29 firmly against said central portion 22. In this adjustment, the portion 29 does not clampingly engage against the domed or upwardly convexed central bearing portion 19, but is held out of clamping engagement therewith by the portion 28 abutting against the central portion 22. These elements pivotally hold the seat on the supporting frame, leave said seat free for rotation about the vertical axis of the pivot device, and prevent tilting or displacement of the seat in any direction.

It is now evident that my invention attains all of its intended objects and purposes in a highly efficient, satisfactory and economical manner. The stool may be composed almost entirely of light-weight and relatively thin-gage sheet metal, the peculiar novel formation and cooperative relationship of the different parts providing the necessary strength to prevent distortion thereof when subjected to the strains and stresses of continuous or repeated use in different environments. The stool is of light-weight, and inexpensive in its construction. I am aware that the particular form and shape of the different elements of the stool may be varied within equivalent limits without departure from the nature and principle of the invention.

I claim:

1. A swivel seat stool, comprising: a pedestal of a plurality of standards, each composed of a flat metal strip shaped to provide a pair of aligned limbs, respectively joined with a limb connecting cross-bar portion of the strip of bowed form extending inwardly between the limbs, thereby with the limbs providing diverging feet for the base of the pedestal, the limbs from their cross-bar connecting end inclined to converge toward each other with their terminals connected to a cap and the bowed cross-bar portion of the several standards centrally intersecting and fixed together, an annularly rimmed sheet metal cap engaged over and fixed to the terminals of the limbs providing a head for the pedestal, the web side of the cap annularly recessed to provide an annular peripheral bearing rib for a seat and a sheet metal seat having a sheet metal hub fixed to and extending centrally from the underside thereof engaged upon said pedestal cap in swivel connection therewith and in bearing contact with the rib thereof.

2. A swivel seat stool, comprising: a pedestal of a plurality of standards each composed of a flat metal strip shaped approximately to an A-configuration providing a pair of aligned converging limbs, and limb connecting cross-bar toward the lower ends of the limbs, and the standards relatively angularly disposed with their cross-bar

portions intersecting and fixed together, a cap connecting the upper terminals of the standards and providing a seat supporting head for the pedestal and a seat having a hub extending centrally from its underside in bearing contact upon the pedestal cap and in swivel connection therewith, the face sides of said hub and cap in relative annular bearing contact by a circumferential ridge extending from the face side of one thereof.
